BALLOT COUNTER

Kellog D. Fleming, San Francisco, Calif., assignor to
Diamond National Corporation, San Francisco, Calif.

Filed June 12, 1970, Ser. No. 23,453

Term of patent 14 years

Int. Cl. D14—02

U.S. Cl. D26—5

FIG. 1.

FIG. 4.

FIG. 2.

FIG. 5.

FIG. 3.

FIG. 6.

FIG. 7.

FIG. 1 is a front elevational view of a ballot counter embodying the new design of my invention;

FIG. 2 is a top plan view thereof;

FIG. 3 is a rear elevational view thereof;

FIG. 4 is a side elevational view thereof;

FIG. 5 is a side elevational view of the other side thereof;

FIG. 6 is a bottom view thereof; and

FIG. 7 is an isometric view thereof.

I claim:

The ornamental design for a ballot counter, substantially as shown.
